UNITED STATES PATENT OFFICE.

GEORGE H. BROWN AND WILFRED E. BURPEE, OF MANCHESTER, NEW HAMPSHIRE.

EXHIBITING OR DISPLAYING APPLIANCE.

SPECIFICATION forming part of Letters Patent No. 629,232, dated July 18, 1899.

Application filed April 22, 1899. Serial No. 714,061. (No model.)

To all whom it may concern:

Be it known that we, GEORGE H. BROWN and WILFRED E. BURPEE, citizens of the United States, residing at Manchester, in the county of Hillsborough and State of New Hampshire, have invented certain new and useful Improvements in Exhibiting or Displaying Appliances; and we do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to an improved appliance for exhibiting or displaying cards and the like, the exhibited or displayed devices being especially designed for use in connection with optical tests.

The object of the invention is to minimize the time and labor incident to the manipulation of the various test-cards and the like; and to this end the invention consists of means by which the exhibition or display of the test devices may be accomplished at a distance from the appliance, thereby enabling the optician to attend closely to the patient and obviating the present necessity of crossing the room at each time a change of a test device is required.

Our invention is designed also to overcome the present necessity of handling the devices in making the various tests, thereby insuring against loss of time and preserving the articles from damage and disarrangement.

The invention in all of its details is fully and clearly set forth in the following description, in which reference is made to the accompanying drawings.

In the drawings, Figure 1 is a sectional view of an exhibiting or displaying appliance embodying our invention. Fig. 2 is a rear elevation, enlarged, of the casing containing the test devices.

Referring to the said drawings by letter, A denotes a casing having a front a , sides a' , and top a^2 . The casing is adapted for attachment to a wall or other upright and con-

tains the test devices, such as the cards B; 50 which are introduced at the back, preferably left open, or at the open lower end. Attached to each of the cards is a cord c , which is passed through an opening a^3 in the top, there being preferably an opening for the cord of 55 each card. Each of the cords is passed around pulleys d d' and is provided at its opposite end with a securing device, such as an eye e , which removably engages a pin f on the opposite wall or other upright adjacent to the patient's chair. Obviously any suitable securing device other than that shown may be provided for each of the cords, and, if desired, the cords may terminate in suitable hand or finger holds. By disengaging an eye e from 60 its hook and elevating the end of the cord the card B, to which it is attached, is permitted to fall by its own gravity, which may, if desired, be augmented by a weight, and said card is thus wholly or partially exposed at the 70 will of the operator below the casing. When another test is to be applied, the cord is drawn down by the operator and its end secured, the card being raised within the casing, and another cord is manipulated to cause the proper 75 card to be exhibited, and so on.

A stop g is provided to limit the downward movement of each card, which stop may, as shown, be secured to the cord to cause its engagement with the top a^2 when the card is in 80 its lowermost position, or this stop may be attached to the cord at any other point—as, for instance, near the opposite end—in which event the stop will engage a suitable shoulder—as, for instance, an eye through which 85 the cord passes or even one of the pulleys over which the cord moves.

If desired, the cards may each be provided on both of the sides with test matter, in which case they can be reversed.

We claim as our invention—

An exhibiting or displaying appliance consisting of a casing open at its lower end and having a closed apertured top, devices such as test-cards adapted to be separately exhibited below the casing and suspended within the casing by cords which are passed through said apertures in the top and carried away.

from the casing for manipulation from a distance, means toward the free ends of the cords for securing them to support the cards in elevated position within the casing, and stops 5 on the cord adapted to engage the casing-top when the cords are released to exhibit the devices below the casing.

In testimony whereof we affix our signatures in presence of two witnesses,

GEO. H. BROWN.

WILFRED E. BURPEE.
